UNITED STATES PATENT OFFICE.

FREDRICH STEHRER, OF BALTIMORE, MARYLAND.

ELECTRIC SWITCH AND LAMP SOCKET.

Application filed August 31, 1921. Serial No. 497,136.

To all whom it may concern:

Be it known that I, FREDRICH STEHRER, a citizen of the United States, residing at Baltimore city, State of Maryland, have invented certain new and useful Improvements in Electric Switch and Lamp Sockets, of which the following is a specification.

This invention relates to sockets for incandescent lamps, and more particularly a 10 socket having incorporated therewith a switch.

The invention has for its object to provide a device of the kind stated which is very simple and cheap in construction, the parts 15 constituting the same being few and arranged so as to be readily assembled.

A further object of the invention is to provide a socket by the use of which a considerable saving of electric current will be 20 effected.

The objects stated are attained by means of a novel combination and arrangements of parts to be hereinafter described and claimed, and in order that the same may be 25 better understood, reference is had to the accompanying drawing wherein—

Figure 1 is an elevation showing one side of the socket; Fig. 2 is a similar view, partly in section; Fig. 3 is a vertical section on the 30 line 3—3 of Fig. 1, and Fig. 4 is a horizontal section on the line 4—4 of Fig. 1.

Referring specifically to the drawing, 5 denotes a screw shell of conducting material, such as brass, adapted to be connected to an 35 attachment plug or similar fixture. The upper end of the shell is closed by a plug 6 of non-conducting material carrying the usual central contact 7 for connection with one side of the service circuit. The lower 40 end of the shell is spanned by a spider 8 of conducting material, which is soldered or otherwise united to the shell to provide an electrical connection. The last-mentioned end of the shell 5 is also closed by a disk 9 45 of insulating material, said disk being secured by screws 10 passing through the spider 8. The contact 7 is a head or enlargement at the upper end of a conductor rod 10' passing centrally through the plug 6, the shell 5, the cross bar 8 and the disk 9, the spider 50 having a perforation 11 large enough to leave the rod out of contact with the same. The rod 10 projects from the disk 9 to pass through a second disk 12 of insulating material, and being formed beneath the latter 55 with a head or enlargement 13 which is en-

gageable by the central contact of the lamp base as usual.

The disk 12 is spaced from the disk 9, and it is carried by bracket arms 14 depending from the latter, said bracket arms being secured by the screws 10, and the disk 12 being secured to the bracket arms by screws 15.

The disk 12 carries a lamp receiving screw shell 16 in which the contact 13 is located, said shell being in axial alinement with the shell 5 and secured to the disk 12 by screws 17. The shell 16 is of course, made of conducting material so that it, with the contact 13, form the circuit connections with the lamp base as usual.

An electrical connection is provided between the shells 5 and 16, and in this connection is interposed a switch. This connection and switch consist of the following parts:

On top of the disk 12 is mounted a pair of contacts 18 which are secured by one of the screws 17, whereby an electrical connection is made between the contacts and the shell 16. To one of the bracket arms 14 is fulcrumed intermediate its ends, as shown at 19, a contact lever 20 having one end arranged to come between the contacts 18. The bracket arm 14 carrying the switch lever 20 is electrically connected to the shell 5, through the screw 10 and the cross bar or spider 8, and hence when said lever engages the contacts 18 there is established an electrical connection between the shells 5 and 16.

The pivot 19 of the switch lever 20 carries a spring 21 which presses on said lever to hold it in circuit-breaking position after it has been swung to that position. The switch lever 20 is operated by the usual pull-chains 22 connected to the ends thereof.

That portion of the device which is below the shell 5 is housed in a sleeve 23 having side slots 24 through which the ends of the lever 20 protrude, and the lower end of the shell 16 is fitted with a flared ring 25 of porcelain which is threaded to screw over said shell, and has an external shoulder 26 against which the lower end of the sleeve 23 seats, and whereby said sleeve is retained in place.

I claim:

A lamp socket comprising a pair of upper and lower spaced screw shells of conducting material, a plug of insulation material closing one end of the upper shell, a contact as-

sociated with said plug, a centrally apertured spider spanning the other end of said upper shell and in electrical contact therewith, a disk of insulation material closing the 5 last named end of said shell, a second disk of insulation material closing the adjacent end of the lower shell and spaced from the first named disk, spacing-brackets arranged between said disks, fasteners passing through 10 said disks and connecting the second named disk therewith and the first named disk with the aforesaid spider, a switch-contact carried by said second named disk, other fastenings securing said lower shell with said last

named lower disk, said other fastenings being in electrical contact with said switch-contact, a spring-pressed circuit closing arm pivoted intermediate its ends on one of the aforesaid spacing-brackets and engageable with said switch-contact, and a rod of conducting material connected with the first named contact on said upper shell and passing through the aperture in said spider, both of said disks and into the interior of said lower shell.

In testimony whereof I affix my signature.

FREDRICH STEHRER.
